UNITED STATES PATENT OFFICE.

FRANCIS M. CROSSLEY, OF DETROIT, MICHIGAN; CORA AURELIA CROSSLEY
GUARDIAN OF SAID FRANCIS M. CROSSLEY, INCOMPETENT PERSON.

SWITCH BOX.

Application filed August 16, 1924. Serial No. 732,442.

To all whom it may concern:

Be it known that I, FRANCIS M. CROSSLEY, a citizen of the United States, residing at Detroit, in the county of Wayne and State 5 of Michigan, have invented certain new and useful Improvements in Switch Boxes, of which the following is a specification, reference being had therein to the accompanying drawings.

10 This invention relates to improvements in switch boxes for the purpose of determining the positive positioning of the tongue or tongues of a switch point in a railroad, having more particular reference to arrangements such as that described in Letters Patent of the United States No. 1,360,270, granted to me Nov. 30, 1920, or No. 1,430,952, granted to me Oct. 3, 1922.

20 In the said prior patent is disclosed switch tongue retaining means wherein a switch retaining member in the form of a spring clip engages a head carried by a slide bar extending from the tongue of a rail in such manner that the said head is secured in either a forward or a retracted position relative to the said retaining member and thus determines the position of the switch tongue.

25 I now propose, and it is an object of this invention, to provide for the adjustment of the said retaining member, within the switch box housing the said retaining member, in order that the device may be easily adapted to various conditions as to location or relation to the switch tongue as may be met with in different installations.

30 It is also an object of the said invention to provide an adjustable support for the retaining member in order to facilitate the adjustment of the said member and to ensure the effectual supporting thereof in its adjusted positions; and the invention still further aims to provide for variation of the operating positions of the said head within the said housing according to requirements.

45 A still further object is to provide a box of this type which is adapted to the housing of different forms of retaining mechanism or members so that the working parts of the switch box may be varied according to requirements and the useful scope of the said box thereby increased.

50 Still further objects subsidiary to or resulting from the aforesaid objects, or from the construction or operation of the inven-

tion as it may be carried into effect, will be 55 come apparent as the said invention is hereinafter further disclosed.

In carrying the said invention into effect I may utilize a switch box or housing for a retaining member such as of the type referred to, in which box various means are provided for the engaging or securing of parts in different adjusted positions therewithin, and more particularly for facilitating the adjustment of the switch retaining 60 member or members relative to the cooperating head of a slide bar extending from the tongue of a railway switch, and a retaining member support adjustable as to position within the said box whereby the active end 65 of the said retaining member may be set at any desirable distance from the front of the box; means being also provided in the said box for the reception of different types of retaining members. All of which is more particularly described and ascertained herein- 70 after, by way of example, having reference to the accompanying drawings, wherein—

75 Figure 1 is a plan of a street railway switch illustrating the application of my invention to the tongue thereof;

80 Figure 2 is a vertical section of the same taken on the line 2^x—2^x Figure 1;

85 Figure 3 is a plan view of the arrangement shown in Figure 2 partly in section and with the cover of the switch box removed to disclose the interior mechanism;

90 Figure 4 is a perspective view of the switch box with all the mechanism and the cover removed therefrom;

95 Figure 5 is a perspective view of a retaining member support;

Figure 6 is a plan of the switch box with the cover removed showing the interior mechanism in one of its adjusted positions;

Figure 7 is a similar view to Figure 1 illustrating an arrangement of the invention as applied to a steam railroad construction;

Figure 8 is a vertical section of the same 100 taken on the line 8^x—8^x Figure 7, and

Figure 9 is a similar view to Figure 4 illustrating the manner of housing the forms of retaining members embodied in the arrangement shown in Figure 7.

105 Similar characters of reference indicate similar parts in the several figures of the drawing. Figures 2, 3, 6 and 8 are drawn

to a larger scale than Figures 1 and 7; and Figures 4, 5, and 9 are drawn to a still larger scale.

Having reference to Figures 1 to 6; 1 indicates a switch tongue movable in a switch mate 2 and having a downwardly projecting lug 3 extending through an orifice 4 in the said mate into the chamber 5, the lateral walls of the said chamber being provided 10 with openings 6. Opposite and, in the example, contiguous to one of the said openings 6 is a switch box or housing 7 provided with openings 8 in its ends and having a cover plate 9 forming a closure for 15 the top thereof. The side walls of the said box have extending from the inner surfaces thereof a series of projections or ribs 10 and the end walls, projections or ribs 11 and 12, the purpose of all of which is herein- 20 after further explained, and these projections terminate below the top of the box and form supporting means for the cover plate 9. 13 are countersunk holes in the ends of the box to permit the securing of 25 the said box in the required position, such as by means of the bolts 14 entering the walls of the mate.

The tongue retaining mechanism comprises a two-way snap switch-retaining 30 member, suitably mounted in the box as will be further described, and comprising a spring clip of a U formation and having a base 16 from which forwardly extend arms 17 having converging end or active portions 35 18 between which a head 19 mounted upon the slide bar 20 is adapted to pass in one or other direction when the tongue is operated. This slide bar extends through one of the openings 6 of the mate and through the op- 40 posed opening 8 of the box.

In operation, the tongue is secured in position lying against one or other of the sides of the mate by reason of the contraction of the end portions 18 of the said retaining member against the resistance of the spring arms 17 when the said tongue is moved to one or other side of the mate as will be well understood.

Due to necessity or desirability the said 50 box may not always be set at the same relative distance from the tongue consequently the head 19 may be disposed and operate in different positions within the box according to circumstances. Or a shorter or longer 55 slide bar may be desirable or other circumstances may influence the operating position of the said head, and in Figure 5 the said head 19 is set closer to the front of the box than is the case in Figure 3. To permit the same box and retaining member to be used in such cases I provide for the adjustment of the position of the said retaining member within the box. This is accomplished through the agency of the ribs 10 60 forming recesses 20 therebetween which are

adapted to receive a support 21 of the said retaining member in such manner that the said support may be received in opposed recesses in the sides of the box and at different points in the length thereof in order to 70 determine the position of the active ends 18 of the said retaining member with respect to the forward end of the box.

This support 21 is shown as having abutments 22 extending more or less around the 75 base of the retaining member and a forward saddle portion 23 spaced therefrom and extending upwardly within the said base portion of the member whereby slots or recesses 24 are provided for the reception of the said member. 25 is an orifice in the upper part of the saddle through which a stud 26 may be passed for the purpose of securing the said member in place in the 80 said support.

It will be noted that the said saddle 23 is also provided with forwardly projecting abutments 27 so that one of the said supports may be inserted in the box behind the support which carries the retaining member as illustrated in Figure 6, the abutments 27 of the additional support bearing against the base of the said retaining member for the purpose of providing additional support therefor. Thus the said retaining 90 member may be rigidly held in all of its adjusted positions.

Under some circumstances, such for instance the arrangement shown in Figures 7 to 9, a modified form of retaining member 100 may be necessary or desirable to suit certain conditions; and in these figures I show the retaining member as comprising two spring plates 28 converging towards one another at their centers and having their ends 105 housed in recesses 29 resulting from the spacing of the projections 11 and 12 on the end walls of the said box 7.

It will be seen from these figures that the said box may be used as with the arrangement shown in Figures 1 to 6 and that the changing of the internal mechanism thereof such as in Figures 7 to 9, may be very readily effected, as all of the mounting 110 of such internal mechanism within the said 115 box is simply effected through the use of the recesses provided between the ribs on the walls thereof.

This invention may be developed within the scope of the appended claims without departing from the essential features of the invention, and it is desired that the specification and drawings be read as being merely 120 illustrative and not in a limiting sense, except as necessitated by the prior art.

What I claim is:—

1. In a device of the class described, a switch box, switch retaining mechanism, and a plurality of ribs on the inner walls of said box, providing for the support of said mech- 125

anism in different adjusted positions in said box.

2. In a device of the class described, a switch box, switch retaining mechanism including a switch retaining member, and a support therefor, said support and said retaining mechanism being adjustable together as to position longitudinally of said box.

10 3. In a device of the class described, a switch box, switch retaining mechanism including a switch retaining member, and a support therefor, and a series of means for the engagement of said support within said box, said support being adjustable longitudinally of said box by engagement with one or other of said means.

4. In a device of the class described, a switch box, switch retaining mechanism including a switch retaining member, and a support therefor, and a series of support engaging means arranged along the inner sides of said box for the adjustable positioning of said support.

5. In a device of the class described, a switch box having a plurality of projecting ribs on the inner sides thereof, a switch retaining member, and a support therefor adapted to be adjustably engaged and positioned by said ribs.

In testimony whereof I affix my signature.

FRANCIS M. CROSSLEY.
